DESIGN FOR A SPECTACLE FRONT

John J. Rohrbach, Rochester, N. Y., assignor to
Shuron Optical Company, Inc., Geneva, N. Y.,
a corporation of New York

Application April 17, 1939, Serial No. 84,349

Term of patent 14 years

To all whom it may concern:

Be it known that I, John J. Rohrbach, a citizen of the United States of America, residing in the city of Rochester, county of Monroe, and State of New York, have invented a new, original, and ornamental Design for a Spectacle Front, of which the following is a specification, reference being had to the accompanying drawing, forming part thereof.

Figure 1 is a front elevation of a spectacle front embodying the present invention;

Figure 2 is a side elevation thereof, parts being broken away; and

Figure 3 is a detail section taken on the line 3—3 of Figure 1.

The essential feature of the design resides in the shape of the lens rim.

I claim:

The ornamental design for a spectacle front, substantially as shown and described.

JOHN J. ROHRBACH.
